UNITED STATES PATENT OFFICE.

WALTER ZABRISKIE, OF PAGOSA JUNCTION, COLORADO.

ROTARY ENGINE.

1,267,157.

Specification of Letters Patent. Patented May 21, 1918.

Application filed March 20, 1917. Serial No. 156,008.

To all whom it may concern:

Be it known that I, WALTER ZABRISKIE, a citizen of the United States, and a resident of Pagosa Junction, in the county of Archuleta and State of Colorado, have invented a new and Improved Rotary Engine, of which the following is a full, clear, and exact description.

My invention has for its object to provide 10 a rotary internal combustion engine which has two cylinders, one used to compress the combustible mixture which is ignited in the other or motor cylinder. The expanding gases act against pistons to rotate a shaft 15 to which pistons in the compressing cylinder are secured, there being a by-pass in a rotatable member disposed in the compressing cylinder and which carries the pistons acting in the said cylinder, to permit the 20 passage of the compressed combustible mixture at the proper time, this combustible mixture passing through a communicating means to the motor cylinder.

Additional objects of the invention will 25 appear in the following specification, in which the preferred form of the invention is disclosed.

In the drawings similar reference characters denote similar parts in all the views, 30 in which—

Figure 1 is a sectional view illustrating my engine;

Fig. 2 is a sectional view on the line 2—2 of Fig. 1; and

Fig. 3 is a sectional view on the line 3—3 of Fig. 1.

By referring to Figs. 1, 2 and 3 of the drawings, it will be seen that each unit of the engine is provided with two cylinders, 40 a compressing cylinder 10 and a motor cylinder 11. In each of the compressing cylinders 10 there is a cylindrical member 12 the diameter of which is less than the inner diameter of the cylinder 10, this member 45 12 being rotatably mounted eccentrically relatively to the cylinder 10 and with its periphery in contact with the cylinder 10 at the outlet port 13 therein. Spaced from the outlet port 13 there is an inlet port 14 50 in the cylinder 10. The rotatable cylindrical member 12 is provided with two guideways 15 which are disposed one at each side of the axis of the rotatable member 12, one of the guideways 15 extending 55 through one side of the member 12 and the other guideway 15 extending through the

opposite side of the said member. In each of these guideways 15 there is a piston 16, the piston 16 being held yieldingly extended by means of springs 17 so that the outer ends of these pistons 16 will be held yieldingly in contact with the cylinder 10 when the member 12 rotates.

As will be seen by referring to Fig. 2 of the drawings, there are two by-passes 18 in the member 12, one of these by-passes being disposed in front of each of the pistons 16. The function of each of these by-passes is to lead the compressed gases to the outlet port 13 when they have been sufficiently compressed between the inner side of the cylinder 10, the periphery of the member 12, and the piston 16. In each pipe 20 there is a check valve 19 the purpose of which is to permit the passage of a fluid from the end 18^b of the by-pass to the inlet motor cylinder port, this check valve 19, however, preventing a movement of the fluid from the inlet motor port to the end 18^a of the by-pass. It will be seen that the end 18^a of the by-pass is offset and cannot communicate with the outlet port 13, and the compressed gases at the said port 13 cannot return to the cylinder 10. The port 14 is connected with a carburetor in a manner readily understood, and the port 13 is connected by means of the pipe 20 with an inlet port 21 in the motor cylinder 11.

Disposed in the cylinder 11 there is a cylindrical member 22, the diameter of which is less than the inner diameter of the cylinder 11, the cylindrical member 22 being rotatably mounted eccentrically relatively to the cylinder 11 and having its periphery in contact with the cylinder 11 at 23. The cylinder 11 is not only provided with an inlet port 20 at one side, but it is also provided with an exhaust port 24 at its outer side. The member 22 is provided with guideways 25 which correspond with the guideways 15 in the member 12, there being slidably disposed in the guideways 25 pistons 26 which correspond with the pistons 16, these pistons 26 being held yieldingly extended by springs 27. The cylinder 11 is provided with a spark plug 28 which is preferably disposed at the side of the cylinder provided with the inlet port 21.

The members 12 and 22 are mounted for rotating on a hollow shaft 29, there being an opening 30 in the member 22 and an opening 31 in the member 12, these open-

ings 30 and 31 registering with the opening in the hollow shaft 29, so that a cooling fluid may flow through the openings 30 and 31 adjacent the guideways 15 and 25, to prevent the springs 17 and 27 from becoming unduly heated.

In the cylinder 10 there are guideways 32 one at each side of the port 13, members 33 being disposed in these guideways 32 which are held yieldingly extended by springs 34. These members 33 serve to prevent the gases from escaping from one side of the cylinder 10 to the other side. In a similar way members 35 are mounted to move in guideways 36 in the cylinder 11, springs 37 being provided for holding the members 35 extended. Packing rings 38 are mounted on the members 12 and 22 at the sides of the pistons 26, as will be seen by referring to Fig. 1 of the drawings.

Having thus described my invention, I claim as new and desire to secure by Letters Patent:

1. In a rotary engine, a compression cylinder having an inlet and an outlet, a motor cylinder having an inlet and an outlet, a member of less diameter than the inner diameter of the compression cylinder disposed in the compression cylinder with its periphery against the wall of the said cylinder at the outlet and rotatable on an axis eccentric to the cylinder, there being a guideway extending out through the periphery of the member, a piston movably disposed in the guideway, there being a by-pass in the member in advance of the piston to lead the gases compressed by the piston to the outlet, means for holding the piston yieldingly against the compression cylinder, and means connecting the outlet from the compression cylinder and the inlet to the motor cylinder.

2. In a rotary engine, two cylinders one a compression cylinder and the other a motor cylinder, disposed side by side each cylinder having an inlet and an outlet, communicating means extending from the outlet of the compression cylinder to the inlet of the motor cylinder, a member of less diameter than the inner diameter of the cylinders disposed in the cylinders, a piston on the member in the motor cylinder, the member being disposed in the compression cylinder with its periphery against the wall of the compression cylinder at the outlet, there being a guideway in the member in the compression cylinder extending out through the periphery of the member, a piston movably disposed in the guideway there being a by-pass in the member in the compression cylinder in advance of the piston to lead the gases compressed by the piston to the outlet in the compression cylinder, and means for holding the piston yieldingly extended against the compression cylinder.

3. In a rotary engine, a compression cyl-

inder having an inlet and an outlet, a motor cylinder having an inlet and an outlet, means connecting the outlet from the compression cylinder with the inlet to the motor cylinder, a member of less diameter than the inner 70 diameter of the cylinders disposed in the cylinders with its periphery against the wall of the compression cylinder at the outlet and rotatable on an axis eccentric to the compression cylinder, there being a guideway extending out through the periphery of the member and disposed in the compression cylinder, a piston movably disposed in the guideway, there being a by-pass in the member in advance of the piston to lead the gases 80 compressed by the piston to the outlet, a spring in the guideway for pressing the piston yieldingly outwardly against the compression cylinder, there being an opening in the member at its axis through which a cooling fluid may be introduced, and a piston on the member disposed in the motor cylinder.

4. In a rotary engine, a compression cylinder having an inlet and an outlet, a motor 90 cylinder having an inlet and an outlet, means affording communication between the outlet in the compression cylinder and the inlet in the motor cylinder, a member of less diameter than the inner diameter of the cylinders 95 disposed in the cylinders with its periphery against the wall of the compression cylinder at the outlet and rotatable on an axis eccentric with the compression cylinder, a piston on the member in the motor cylinder, there being two guideways in the member in the compression cylinder one at each side of its axis extending through the periphery of the member, pistons movably disposed in the guideways, there being two by-passes in the 100 member one in advance of each piston to lead the gases compressed by the pistons to the outlet at the proper time, and means for holding the pistons yieldingly extended against the compression cylinder. 110

5. In a rotary engine, a compression cylinder having an inlet and an outlet, a member of less diameter than the inner diameter of the compression cylinder disposed in the compression cylinder with its periphery 115 against the wall of the cylinder at the outlet and rotatable on an axle eccentric to the cylinder, and a piston movably mounted on the member for engaging the inner wall of the compression cylinder, there being a by-pass in the member in advance of the piston to lead the gases compressed by the piston to the outlet. 120

6. In a rotary engine, a compression cylinder having an inlet and an outlet, a motor 125 cylinder having an inlet and an outlet, a member of less diameter than the inner diameter of the compression cylinder disposed in the compression cylinder with its periphery against the wall of the compression cylinder 130

at the outlet therein, the member being rotatably mounted on an axis eccentric to the compression cylinder, there being a guideway extending out through the periphery of the member, a piston movably disposed in the guideway, there being a by-pass in the member in advance of the piston to lead the gases compressed by the piston to the outlet, means for holding the piston yieldingly extended against the cylinder, a member of less diameter than the inner diameter of the motor cylinder disposed in the motor cylinder with its periphery against the wall of the motor cylinder between the inlet and the outlet, there being a guideway in the second mentioned member which extends through its periphery, a piston in the last mentioned guideway, means for holding the last mentioned piston yieldingly extended against the motor cylinder, igniting means in the motor cylinder, a shaft on which the two members are mounted, and a communicating means connecting the outlet in the compression cylinder with the inlet in the motor cylinder.

WALTER ZABRISKIE.
